[57] ABSTRACT

An apparatus for facilitating the withdrawing of gases from a gas filled chamber such as a coke oven comprises a connecting conduit having a riser portion with a lower end connected into the gas chamber and an opposite end connected into a gas receiving tank. The riser includes a bend portion extending downwardly from the top of the riser toward the discharge of the conduit in which is mounted a liquid nozzle. The liquid nozzle is universally pivotally mounted on a ball member which is guided in a socket carried by the wall of the bend portion of the conduit. The nozzle may be oriented in a selected direction to discharge downstream at a selected angle for varying the withdrawal pressure acting on the gases which move upwardly through the riser to the receiving tank.

**APPARATUS FOR FACILITATING THE
WITHDRAWAL OF GASES FROM A GAS FILLED
CHAMBER SUCH AS A COKE OVEN**

BACKGROUND OF THE INVENTION

1. Field of the Invention

This invention relates in general to the construction of devices for facilitating the withdrawal of gases from chambers such as a coke oven and in particular to a new and useful device from withdrawing gases from the top of a coke oven which includes a conduit having a riser portion and a bend portion with a nozzle universally pivotally mounted within the bend portion so that liquid from the nozzle may be sprayed into the conduit downstream of the riser at a selected angle in order to vary the withdrawal pressure for removing the gases.

2. Description of the Prior Art

Devices are known for withdrawing filling gases from coke oven batteries and directing them into receivers and which use liquid jet nozzles for regulating the withdrawal pressures. Such nozzles are mounted in the bend of the conduit downstream of the rising tube and they are oriented in a fixed direction to direct the gases upwardly through the riser and through the bend portion of the conduit. Such tubes discharge liquid in the form of gas water or coal water as a scavenging medium under low pressure during the carbonizing period and as a pressure medium under high pressure of more than 6 atmospheres in excess during the charging period. A particularly efficient means for this purpose are full-cone nozzles having an angle of dispersion of from between 60° and 65° and which are provided with a swirl insert and which are positioned under an angle of 90°. Such nozzles are frequently capable of producing satisfactory low pressures and their scavenging effect is more than sufficient. However the effect of the nozzle depends on the shape of the bend downstream of the riser portion of the conduit so that in a fixed position the nozzle cannot operate with an optimum efficiency in all circumstances. In consequence in order to obtain a sufficiently low pressure, it is frequently necessary to use a higher water pressure and also a larger volume of water. The economy of the plant is thereby affected.

In addition the shape of the bend of the rising tube depends on the structural arrangement of the coke-oven battery and it cannot be foreseen in what position the nozzle will be most effective. Complicated time-consuming tests must be made which require a repeated mounting and demounting of the nozzle as well as additional mechanical work.

SUMMARY OF THE INVENTION

The present invention provides an apparatus which includes a conduit having a riser portion with an inlet connected to the gas chamber or top of the coke oven and an opposite discharge end connected into a receiving tank. The conduit includes a bend between the discharge and the riser having a pivotal nozzle thereon which may be oriented in a selected angular direction for directing water into the conduit downstream of the riser. The nozzle is universally pivotally mounted so that it may be easily adjusted to an optimum angular position to effect a maximum efficiency in operation to withdraw the gases from the coke oven. The nozzle may be pivoted during use in order to permit it to be set at a desired angle to effect the most optimum gas withdrawal rate. The nozzle includes a ball member

which is universally pivotally mounted on a receiving ball socket formed in a wall of a bend portion of the conduit. The nozzle may be oriented in all directions and its outer end is connected to a liquid supply conduit. The ball is advantageously located in the conduit in the bend portion or in the upper portion of the nozzle riser. A particularly advantageous arrangement is to mount the pivotal ball in the bend portion of the connecting conduit adjacent the top end of the connecting tube. The nozzle exterior is advantageously connected to a flexible water supply conduit. During operation it may be oriented in any selected angular position to achieve optimum gas flow. This optimum position may be easily determined within a short time by providing a manometer on the rising tube to indicate the pressure corresponding to each individual position of the nozzle. A locking member retains the ball feed in the optimal operative position of the nozzle after it is set.

Full-cone nozzles have proved to be the most suitable ones. In case the ball seat is located at the top of the connecting tube between the riser and the bend portion it is advantageous to mount the nozzles for adjustment within an angle of angle β equals 30° to 60°. The appropriate swivelling range δ of the ball seat is 10° to 20°. The nozzles are also advantageously provided with swirl inserts.

Accordingly it is an object of the invention to provide an apparatus for facilitating the withdrawal of gases from gas filled chambers such as coke ovens which comprises a connecting conduit having a riser portion with a lower end connected to the gas chamber and an upper end portion which extends downwardly from the top of the riser portion into a gas receiver and which includes a liquid nozzle which is universally pivotally mounted in said conduit downstream of the top of said riser and which includes an upper end of the nozzle which is exterior of the conduit for connection to a water supply hose and an interior end which is directed downwardly in a selected direction downstream of the riser in order to facilitate the withdrawal of the gas through the riser and bend portion through the receiving chamber.

A further object of the invention is to provide an apparatus for withdrawing gas from a coke oven which is simple in design, rugged in construction and economical to manufacture.

For an understanding of the principles of the invention, reference is made to the following description of a typical embodiment thereof as illustrated in the accompanying drawing.

**GENERAL DESCRIPTION OF THE PREFERRED
EMBODIMENT**

Referring to the drawing in particular, the invention embodied therein comprises an apparatus generally designated 50 for use in withdrawing gases from a gas chamber 8 of a coke oven generally designated 52 having a top wall or cover 10.

In accordance with the invention the apparatus 50 includes a conduit generally designated 54 which includes a vertically extending riser portion 5 having a lower end which is connected into the chamber 8 and an upper portion which is connected to a bend portion 9 and a bend portion 4 which has a lower discharge end 4a which connects downwardly into a gas receiving chamber 6 defined within a collecting main 56 which is mounted on foundation supports 14 and base blocks

13 over a foundation 12 connected with the back stay 11. In accordance with a feature of the invention a nozzle generally designated 1 is universally pivotally mounted in a wall 58 of a bend portion 9 of the conduit 54. In the embodiment shown the nozzle 1 includes a ball shaped mounting portion 1a which is mounted for universal pivotal movement in a spherical socket 2 of the wall 58. The inner lower end of the nozzle 1 may be directed at any selected angle in accordance with the pivotal orientation of the ball portion 1a in the socket 2. The outer or upper end of the nozzle 1 is provided with a connection flange 60 for connecting the nozzle to a flexible conduit 3. Water is supplied to the conduit 3 which is discharged in a stream from the lower end of the nozzle 1 and this spray stream may be regulated in order to achieve the desired withdrawal pressure in the riser tube portion 5 of the conduit 54.

A locking member 7 may be adjusted in respect to the socket seat 2 to lock the nozzle 1 in an adjusted position.

The nozzle 1 may be pivoted through an adjusting angle β and the swivelling angle δ of the nozzle is also indicated.

With a full-cone nozzle 1 having a swirl insert and a diameter of 7.5 mm and at a nozzle adjustment angle of $\beta = 45^\circ$, a water pressure at the nozzle of 30 atmospheres in excess and a rate of flow of the water at 120 liters per minute, an under-pressure of 70 mm of water column is obtained in the rising tube 5. At the same rate of flow and with the water pressure at the nozzle of from 15 to 20 atmospheres in excess, the measuring indicated that a water column of 20 mm up to 45 mm underpressure may be obtained.

While a specific embodiment of the invention has been shown and described in detail to illustrate the application of the principles of the invention, it will be understood that the invention may be embodied otherwise without departing from such principles.

What is claimed is:

1. An apparatus for facilitating the withdrawal of gases from a gas filled chamber such as a coke oven to a gas receiving chamber, comprising a connecting conduit having a riser portion with a lower end connected into the gas chamber and an opposite upper end, a bend portion extending downwardly from the upper end of said riser portion and having the lower discharge end connected to the gas collecting main, and a liquid nozzle universally pivotally mounted in said bend portion having an upper end extending exteriorly of said conduit and an opposite end directed downwardly into said conduit in a selected angular orientation downstream of said riser in order to facilitate withdrawal of the gas through the riser and bend portion to the receiving chamber.
2. An apparatus according to claim 1, wherein said bend portion includes a conduit wall having a spherical socket, said nozzle including a ball portion universally pivotally mounted on said spherical socket.
3. An apparatus according to claim 1, wherein said riser portion includes a vertical tube part, said bend portion including a separate connection tube having a vertical part connected into said riser part and a downwardly extending bend part having a wall carrying said nozzle.
4. An apparatus according to claim 1, wherein said bend part includes a top wall portion having a spherical socket carrying said nozzle.
5. An apparatus according to claim 1, wherein said nozzle comprises a full-cone nozzle.
6. An apparatus according to claim 1, wherein said nozzle includes a ball member, said conduit having a spherical cavity pivotally supporting said ball member for swivelling about an angle of from 30° to 60° .
7. An apparatus according to claim 1, wherein said nozzle may swivel in the range of from 10° to 20° .
8. An apparatus according to claim 1, including a swirl insert provided in said nozzle.
